(57) **CLAIM**

The ornamental design for a media gateway, server and storage device, as shown and described.

DESCRIPTION

FIG. 1 is a front left perspective view of the media gateway, server and storage device showing our new design;

FIG. 2 is a left side view thereof;

FIG. 3 is a right side view thereof;

FIG. 4 is a top view thereof;

FIG. 5 is bottom view thereof;

FIG. 6 is a rear view thereof; and,

FIG. 7 is a front view thereof.

The broken lines showing other elements in the Figures are for illustrative purposes only and form no part of the claimed design.
